UNITED STATES PATENT OFFICE

155,322

DESIGN FOR A COIN DISPENSER

Lyle Forrest Pierce, Watsonville, Calif., assignor of fifty per cent to Steve V. Beuson, Watsonville, Calif.

Application June 16, 1948, Serial No. 147,002

Term of patent 3½ years

(Cl. D52—4)

To all whom it may concern:

Be it known that I, Lyle Forrest Pierce, a citizen of the United States, residing at Watsonville, in the county of Santa Cruz and State of California, have invented a new, original, and ornamental Design for a Coin Dispenser, of which the following is a specification, reference being had to the accompanying drawing, forming part thereof.

and

I claim:
The ornamental design for a coin dispenser, as shown.

LYLE FORREST PIERCE.
